UNITED STATES PATENT OFFICE.

WILLIAM H. MILLER, OF SOUTH BEND, INDIANA, ASSIGNOR TO THE MILLER-KNOBLOCK COMPANY, OF SAME PLACE.

SPRINKLING-CAR.

SPECIFICATION forming part of Letters Patent No. 590,999, dated October 5, 1897.

Application filed February 25, 1897. Serial No. 625,044. (No model.)

To all whom it may concern:

Be it known that I, WILLIAM H. MILLER, a citizen of the United States, residing at the city of South Bend, in the county of St. Joseph and State of Indiana, have invented a certain new and useful Sprinkling-Car, of which the following is a specification.

My invention relates to improvements in sprinkling-cars which are used for the purpose of sprinkling streets and the tracks of street-railways and for similar purposes.

The objects of this invention are, first, to provide a sprinkler of large capacity which is under complete control, so that water can be distributed over the full width of a street or roadway or be thrown down and limited to any required width or be quickly cut off without difficulty or injury. A further object is to provide a street car-sprinkler in which a force-pump or other pressure device is used which can be quickly shut off for convenience in passing teams or persons at a high speed on the street or highway; third, to provide an improved rotary pump for use in this connection; fourth, to provide improved means of controlling a rotary pump; fifth, to provide a sprinkler that shall be economical in the amount of water consumed. Further objects will appear definitely in the detailed description. I accomplish these objects of my invention by the devices, means, and mechanism described in the following specification and illustrated in the accompanying drawings, in which—

Figure 1 is a side elevation of the front part of a sprinkling-car with one of my improved sprinklers in place. Fig. 2 is an end elevation of the same with portions of the tank and platform broken away to show the details of construction. Fig. 3 is an enlarged detail vertical sectional view through the sprinkler-head and force-pump and adjacent parts, taken on line 3 3 of Figs. 4 and 5. Fig. 4 is an enlarged transverse detail sectional view through the sprinkler, taken on line 4 4 of Fig. 3. Fig. 5 is an enlarged detail transverse sectional view taken on line 5 5 of Fig. 3. Fig. 6 is an enlarged detail perspective view of the controlling cylindrical shell D. Fig. 7 is an enlarged detail perspective view of one of the wings F of the rotary pump with the roller removed. Fig. 8 is an enlarged detail

view of the transverse lever K for rotating the shell D. Fig. 9 is an enlarged detail view of the connections for operating the lever shown in Fig. 8.

In the drawings all of the sectional views are taken looking in the direction of the little arrows at the ends of the section-lines, and similar letters of reference refer to similar parts throughout the several views.

Referring to the lettered parts of the drawings, A is the platform of the car. On this platform is supported the usual large tank T, in which the supply of water for sprinkling is carried. Trucks of suitable form are under the platform. No motor is shown for the car and none for the sprinkling device, as this invention does not relate to the motors. Any suitable or convenient motor or means for the purpose can be adopted. As for the sprinkling-car itself, instead of a motor on the car it may be propelled by an independent motor-car or engine or be drawn by horses.

Across the front of the platform cross-beams A' A' are placed, which carry the sprinkler or head. A delivery-pipe M extends down from the tank T and connects with the sprinkler-head, the details of which will be hereinafter definitely pointed out. The sprinkler-head consists of an external casing B, which is supported on the under side of the platform by the suitable bolts L, extending through suitable ears, and a band around the under side of the same. Within this casing B is a movable cylindrical shell D, which is shorter than the external casing. Through the sides of the shell are a series of sprinkler-openings b, the openings toward the top of the cylinder being larger and the openings toward the bottom being smaller, so that water delivered through the same will be thrown to a considerable distance by the upper openings, while it will be thrown in a fine spray on the ground or street immediately beneath the sprinkler and prevent "washing" of the street or pavement. This interior shell D is adjustable back and forth longitudinally and is also rotatable. The casing B is provided with an opening N at one side to permit of the passage of the spray from the cylinder D and with an inlet-opening to which the hose M from the tank T connects. The interior shell or cylinder D is also provided with in-

let-openings *c*, which come when adjusted back and forth in front of the openings to which the hose *M* connects. The casing *B* is provided on its rear end with a head *B''*, which is secured thereto water-tight by suitable means. This head carries also an additional head *G'*, by means of the arm *G*, which reaches into the shell *D* and over which the shell *D* is adjustable. The head *G'* comes just back of the opening *N*, through which the spray is delivered. A head *B'* is also on the front end of the cylindrical case *B*. This also bears a head *H'*, which reaches back to a distance just in front of the opening *N* and is secured by an arm *H* to the front head *B'*. The cylindrical shell *D* is adjustable over this head also.

The cylindrical shell *D* is provided with a partial head *D'*, which contains a curved slot and openings for the passage of the water freely through the same, so that it can be moved back and forth freely inside of the main shell *B* when the water is under pressure. A rock-shaft *D''* extends through the head *B'*, where it is packed by a suitable stuffing-box, and through a curved slot in the partial head *D'* of the shell *D*. It is secured there loosely by a nut inside the shell. An arm *I*, containing a radial slot, is fixed to the shaft *D''*, and a pin *I'* to the partial head *D'* extends into this slot, so that when the shaft *D''* is out, or pulled out and in, it will adjust the shell *D* longitudinally, so it will be seen that the shell *D* is controlled from the shaft *D''*. Between the heads *G'* and *H'*, above referred to, within the shell *B* is a rotary pump fixed on the shaft *C*, extending through the shell *D* and the exterior casing *B*, and is carried on a suitable packed bearing in the heads *B'B''*. The pump is made up of a cylindrical head *C'*, (see Figs. 3 and 4,) having radial guide-openings therein. In the radial recesses are supported radially-movable wings *F*, having antifriction-rollers *F'* thereon positioned to traverse the interior of shell *D* when the head *C'* is rotated. The head is operated by rotating the shaft *C*, which can be done by any suitable power which I have hereinbefore indicated.

Pivoted at *a* on the platform is a lever *J*, which extends down and is pivoted on a collar on the end of the shaft *D''*. This lever is to move the shaft *D''* out and in and adjust the shell *D* longitudinally. A cross-lever *K* is fixed on the shaft *D''*, and a cross-lever *K'*, with a handle *K''*, is pivoted on the upper part of the lever *J* and is connected to lever *K* below by connecting-rods *J' J'*, so that the rock-shaft *D''* can be rocked back and forth by the cross-lever *K'* above, adjusting the shell *D* rotatably within the exterior shell *B*.

From the description I have given it will be noted that when the sprinkler-car is in operation and the pump is being revolved the operator has complete control of the amount of water passing through the same by merely pushing the lever *J* back and forth,

and when desired to limit the space sprinkled he has only to turn the cylinder *D* down by means of the lever *K'*, when the direction of the spray will be deflected. The combination of these devices makes the change of the direction of the spray or varies the space covered and controls the quantity of water to secure the sprinkling over a broad or narrow space simultaneously. This means of controlling a force-pump is an advantage in that it limits the supply of water to the pump at the same time it limits the outlet therefrom, and if the movement of the shell is continued it entirely shuts off the supply of water to the pump, as well as the spray, thus shutting off the device and enabling the same to be done substantially instantaneously without any strain on the machinery.

Having thus described my improved car-sprinkler head, I desire to state that it is capable of great variation in its details without departing from my invention.

I am aware that other styles of pumps have been produced than the one I have used capable of this use. I also desire to state that different means than the exact means I have employed for adjusting the shell might be easily devised. The shell *D* might be utilized with other means for forcing the water through the same and serve its purpose very well indeed. Other means of guiding and securing the shell *D* might be employed than the outer casing *B*, though the exact means that I have used is believed to possess great merit over any other. This construction might be reduced in size and be utilized on sprinkling-wagons and would be found very efficient in that position. As for the pump itself the exact mechanism might be utilized in other relations than I have here illustrated or described.

Having thus described my invention, what I claim as new, and desire to secure by Letters Patent, is—

1. In a sprinkling-car, the combination of a suitable car; a supply-tank *T*, having a delivery-pipe *M*, supported thereon; a sprinkler-head consisting of the outer shell *B*, with delivery-opening *N*, toward the middle of one side and an opening on the opposite side for said delivery-pipe *M*; an inner shorter cylindrical shell *D*, with a head *D'*, freely movable fitted within shell *B* and therein either revolvably or longitudinally containing perforations *b*, to deliver spray and openings to receive water from the tank; a head *B''*, for the rear end of the outer shell *B*, with a head *G'*, secured thereto by the arm *G*, and extended into the inner shell *D*, to the rear of the opening *N*; a head *B'* for the front of the outer shell *B*, with a head *H'*, secured thereto just in front of opening *N*, extended into the shell *D*, through an opening in the head *D'*; a rock-shaft *D''*, extending through a suitable stuffing-box in the head *B'*, and through a curved slot in head *D'*, and secured to the head by a nut on the inside; an arm *I*, with slot therein

secured to said shaft D'', and fitting close to the face of head D'; a pin I', on said head to be engaged by the slotted arm I; a lever J, pivoted to the platform of the car and to the outer end of the said shaft D'', by suitable pivots on a revoluble collar; a cross-arm K, fixed on the shaft D'', an arm K', with handle pivoted to the lever J, and substantially parallel to arm K; connecting-rods I', joining the arms K, K', together; a rotary pump supported in the chamber between the heads G, and H, and a driving-shaft C, supported in packed bearings in the heads B', B'', to drive said pump all coacting together substantially as described for the purpose specified.

2. In a sprinkler-head the combination of an outer cylindrical shell B, with a delivery-opening N, in one side and a supply-opening in the opposite side; a shorter cylindrical shell D, fitted within the outer shell B, freely movable therein either revolvably or longitudinally, containing sprinkler-perforations b, in one side and inlet-openings c, on the opposite side, having a head D', on its forward end; a head B', for the rear end of the outer shell B, with a head G', secured thereto by arm G, and extended into shell D, to a point just to the rear of the opening N; a head B', for the front end of shell B, with a head H', secured thereto just in front of opening N, by arm H, extended through head D'; a rock-shaft D', extending through a stuffing-box in head B', and through a slot in head D', and secured to said head by a nut inside the head; an arm I, with a slot therein secured to said shaft; a pin I', on the head D', to be engaged by said arm; suitable means of actuating said shaft to control the shell D; a rotary pump in the chamber between the heads G', H', with suitable means of actuating the same as specified.

3. In a sprinkler the combination of an outer shell with suitable heads having broad delivery and inlet openings; an inner cylindrical shell fitting the interior of said outer shell and freely movable both revolvably and longitudinally therein, and having spray-openings b in one side and inlet-openings c, in the opposite side, corresponding to the openings in the outer shell, heads within said inner movable shell to each side of the openings of the outer shell and supported in a fixed position by suitable connections to the heads of the outer shell; a rotary pump in the chamber between the inner heads; a source of supply for said pump; and suitable means of adjusting the inner shell to control the spray as specified.

4. In a sprinkling device the combination of a suitable means for forcing the water; a sprinkler-shell containing inlet-openings at one side and outlet spray-perforations on the opposite side graded in size from the upper to the under side to throw a heavy spray for the longer distance and a finer spray for the

shorter; and means of adjusting said shell rotatably and longitudinally to regulate the direction and amount of the spray as specified.

5. In a sprinkler-head an external casing with openings therein for receiving water and to allow the escape of a spray; an interior cylindrical shell adjustable longitudinally and revolvably within the outer casing and containing inlet-passages and outlet-perforations for delivering spray the said outlet-openings being largest toward the top side of the cylinder; heads to the outer casing bearing heads which project within and fit the interior cylindrical shell; a rotary force-pump within the interior shell and between the heads with means of actuating the same as specified.

6. In a sprinkler a rotary pump and a cylindrical shell surrounding the same containing spray-perforations, as specified.

7. In a sprinkler a rotary pump, a cylindrical shell surrounding the same containing a series of spray-perforations those toward the top being largest; and suitable means of adjusting the shell longitudinally to cut off, and rotatably to deflect the spray as specified.

8. In a sprinkler a rotary pump; a cylindrical shell surrounding the same containing a series of inlet-ports on one side corresponding to the width of the pump and a series of outlet spray-perforations on the opposite side also of a width corresponding to the width of the pump and larger toward the top of the cylinder than at the bottom, suitable means of adjusting the cylindrical shell longitudinally to regulate the inlet and outlet; and suitable means of adjusting the cylinder rotatably to deflect the spray for the purpose specified.

9. In a sprinkler a rotary pump; a cylindrical shell surrounding the same containing a series of inlet-ports to one side, corresponding to the width of the pump and a series of outlet spray-perforations on the opposite side also of a width corresponding to the width of the pump and suitable means of adjusting the cylindrical shell longitudinally to regulate the pump, simultaneously regulating the inlet and outlet; and suitable means of adjusting the cylinder rotatably to deflect the spray for the purpose specified.

10. In a sprinkler a rotary pump; a cylindrical shell surrounding the same containing a series of inlet-ports to one side corresponding to the width of the pump and a series of outlet spray-perforations on the opposite side also of a width corresponding to the width of the pump; suitable means of adjusting the cylindrical shell longitudinally to regulate the pump, simultaneously regulating the inlet and outlet for the purpose specified.

11. In a sprinkler a rotary pump; a cylindrical shell surrounding the same containing a series of inlet-ports on one side corresponding to the width of the pump and a series of

outlet spray-perforations on the opposite side also of a width corresponding to the width of the pump and suitable means of adjusting the cylinder rotatably to deflect the spray for the purpose specified.

12. In a sprinkler the combination of a forcing means; a cylindrical shell to receive the water and with a series of outlet-openings on one side those toward the top being largest; and suitable means of adjusting said shell longitudinally to regulate the amount and rotatably to control the direction of the spray to sprinkle a broad or narrow strip for the purpose specified.

13. In a sprinkler-car the combination with the tank and platform of the car; of a suitable forcing means; a cylindrical shell D, to receive the water, having a series of spray-openings on one side; a shaft connected to said shell; a lever J, connected to a collar on said shaft to adjust the same longitudinally; a cross-lever K, fixed on said shaft; a cross-lever K', fixed on said lever J, and connections J', J', between levers K and K', to rock the shaft

and adjust the cylinder rotatably for the purpose specified.

14. In a sprinkler the combination with a supply-tank of a suitable forcing means; a cylindrical shell to receive the water having a series of spray-openings on one side; a shaft connected to said cylindrical shell; a lever connected to said shaft to adjust the shell longitudinally to regulate the amount of flow; a cross-lever fixed on said shaft with suitable connections to adjust the shell rotatably to control the direction of the spray for the purpose specified.

15. In a sprinkler, a rotary pump, a shell surrounding the same containing suitable spray-openings and a supply-passage leading to the pump for the purpose specified.

In witness whereof I have hereunto set my hand and seal in the presence of two witnesses.

WILLIAM H. MILLER. [L. s.]
